(57) **CLAIM**

The ornamental design for an audiovisual terminal, as shown and described.

DESCRIPTION

FIG. 1 is a front, side perspective view of an audiovisual terminal showing my new design;

FIG. 2 is a rear, side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The portions of the audiovisual terminal shown in broken lines in FIG. 2 and FIGS. 4, 5, 6 and 8 form no part of the claimed design.
